UNITED STATES PATENT OFFICE.

HARRY GUY BARTHOLOMEW AND HERBERT MONT BUSSY, OF LONDON, ENGLAND.

APPARATUS FOR THE PRODUCTION OF PROCESS PRINTING-PLATES.

No. 899,019.

Specification of Letters Patent.

Patented Sept. 22, 1908.

Application filed September 10, 1907. Serial No. 392,243.

To all whom it may concern:

Be it known that we, HARRY GUY BARTHOLOMEW and HERBERT MONT BUSSY, subjects of the King of Great Britain and Ireland, residing at London, England, have invented new and useful Improvements in Apparatus for the Production of Process Printing-Plates, of which the following is a specification.

10 This invention has reference to an improved apparatus for the production of half-tone, line, and other process printing plates.

It has for its object to reduce the time occupied in the etching of such plates, and 15 thereby the cost of the labor required therefor, and it is particularly designed for use in the preparation of plates for newspaper work, in which pictorial representations of current events are given, wherein a saving 20 in the time required for etching plates is of considerable importance and value.

For this purpose the present invention consists in the provision of apparatus whereby the whole surface of the plate to be etched 25 is brought, while in horizontal, or approximately horizontal, position, into rapid and repeated contact with the surface of the acid bath, instead of permitting the acid to flow backward and forward over same, or to be 30 pumped or thrown on to the plate as heretofore usual.

In order that the details of construction and the action of the invention may be clearly understood, reference is made to the accompanying drawings, in which:—

Figure 1, is a cross sectional elevation and Fig. 2 a front elevation of the improved apparatus. Figs. 3 and 4, are a plan and cross section respectively, on a slightly enlarged 40 scale, of the frame for holding the plates during the process of etching.

Fig. 1, is a vessel for the acid bath composed of porcelain or other suitable material. It may be constructed as shown in one piece with the 45 vessel *b* for the water bath, or separately, as desired.

c, is a plunger attached to the lower end of a vertically reciprocating rod *d*, which passes through a suitably bushed opening formed 50 centrally in the cover *a*, of the vessel *a*. The upper end of the rod *d*, is bifurcated, and each of the bifurcated arms *e*, *e'*, has inwardly projecting studs, *f*, *f'*, which take into a cam path *g*, formed on each face of the cam plate

h, which is fixed eccentrically on the shaft *i*, 55 to which rotary motion is imparted through the band wheels *j*, *j'*.

k, is a door or shutter of aluminum, or other suitable material which will resist the action of the acid, for closing the opening *l*, 60 in the front of the vessel *a*. It is supported by counterbalance weights *m*, which run over pulleys *n*, in suitable openings formed in the upper portion of the wooden framework *A*, by the portions *A*', of which the 65 shaft *i* is also carried.

The operation of the apparatus is as follows:—The plates *O*, *O'*, *O''*, are placed in the usual manner in the frame *p*, which has its sides beveled to enable it to slide, when 70 passed through the opening *l*, into the correspondingly shaped under face of the plunger *c*. When the frame *p*, containing the plates to be etched is in position in the plunger, the surfaces to be etched are face downwards. The opening *l*, is then closed by lowering the door, or shutter *k*, and on motion being imparted to the wheel *j*', by the handle *q*, such motion will be transmitted by the band *s*, to the wheel *j* on the end of the 75 shaft *i*, which will cause the cam plate *h*, to revolve. The projecting studs *f*, *f'*, secured to the bifurcated arms *e*, *e'*, of the rod *d*, will thereupon be caused to travel in the annular path *g*, on each face of the plate *h*, the resultant vertically reciprocating motion bringing the plunger *c*, and with it the surfaces of the plates *O*, *O'*, *O''*, into rapid and repeated contact with the surface only of the acid in the bath *a*. When the plates have been 80 sufficiently etched the shutter *k*, is raised and the frame *p*, withdrawn from the plunger *c*, through the opening *l*, by means of the handle *r*, when it is deposited in the water bath *b*, to be washed in the usual manner. 85

We are aware that prior to our invention etching apparatus with reciprocating plungers operating in acid baths have been proposed. We do not claim such a combination broadly; but

What we do claim as of our invention, and desire to secure by Letters Patent, is—

An apparatus for etching half tone or other printing plates comprising a closed chamber having an opening therein, a door 105 closing said opening, a vessel adjacent said chamber and opposite the opening therein, a plunger in said chamber, a rod connected

to the said plunger, a cam engaging with the rod for reciprocating the same, means for rotating the cam, said plunger having a recess in its under face provided with beveled edges and a plate carrying frame having beveled edges adapted to engage in said recess.

In testimony whereof we have signed our

names to this specification in the presence of two subscribing witnesses.

HARRY GUY BARTHOLOMEW.
HERBERT MOIR BUSSEY.
